UNITED STATES PATENT OFFICE.

E. WINGATE HARRISON, OF JERSEY CITY, NEW JERSEY.

DESIGN FOR A CAMPAIGN BADGE.

Specification forming part of Design No. 5,919, dated June 11, 1872.

Specification describing a Design for a Campaign Badge, invented by E. WINGATE HARRISON, of Jersey City, in the county of Hudson and State of New Jersey.

In the accompanying drawing, Figure 1 is an elevation of said badge as attached to a ribbon. Fig. 2 is a side view of the badge, and Fig. 3 is a rear view.

This badge is a presidential campaign badge, representing a soft felt hat with the rim *a* turned up and the rounding crown *b* as slightly indented.

The drawing represents the shape and configuration of this badge in about the actual size.

I claim as my invention—

The design of the shape and configuration of the campaign badge, as represented.

Signed by me this 10th day of May, A. D. 1872.

E. WINGATE HARRISON.
